2 SHEETS—SHEET 2.

UNITED STATES PATENT OFFICE.

FRIEDRICK GITTINGER, OF JERSEY CITY HEIGHTS, NEW JERSEY.

KEG-TAPPING DEVICE.

1,065,233.

Specification of Letters Patent. Patented June 17, 1913.

Application filed November 11, 1912. Serial No. 730,757.

To all whom it may concern:

Be it known that I, FRIEDRICK GITTINGER, a citizen of the United States, residing at Jersey City Heights, in the county of Hudson and State of New Jersey, have invented certain new and useful Improvements in Keg-Tapping Devices, of which the following is a specification.

My invention relates to devices for tapping kegs and barrels, and has especial reference to devices for tapping kegs of beer, and has for its object the provision of an improved construction of tapping devices comprising a bung having an integral web 10 provided with an opening and segmental slots, rotatable valve members mounted on the two sides of said web and secured together for simultaneous rotation over said segmental slots, and a nozzle member adapted 15 to enter and be locked in engagement with said bung and provided with means for rotating the valve members when moving into locking position.

My invention will be described in detail 20 hereinafter and illustrated in the accompanying drawings, in which,

Figure 1 is a vertical sectional view of a keg showing my improved tapping device applied thereto and shown in elevation; Fig. 2, a vertical sectional view of the tapping device showing the nozzle in position and the tapping tube extended through the valve and bung; Fig. 3, a vertical sectional view of the bung member on a plane 90° 35 removed from the plane of the section in Fig. 2, showing the valve in a closed position; Figs. 4 and 5, plan views of the bung in closed and open positions respectively; Fig. 6, a plan view showing the top plate 40 of the valve structure removed; Fig. 7, a view in perspective of the top plate of the valve; and Fig. 8, a bottom plan view of the nozzle.

In the drawings similar reference characters will be used to designate corresponding parts throughout the several views.

In Fig. 1, my improved tapping device is shown applied to a keg designated A and consists essentially of the two members designated 1 and 2, being the bung member engaging the head of the keg A and a nozzle member that is removably secured within the bung member 1. The bung member 1 is substantially cylindrical in contour and provided with the screw threads 1^a that engage the head of the keg. The bung member 1 is

also provided with a web 3 intermediate of its top and bottom, said web 3 having an opening 4 therein eccentric of the bung member 1 and concentric segmental slots 5. 60 The upper edge of the bung has inwardly extending flanges 6 with inclined lower edges 7, said flanges 6 having their terminals spaced apart as clearly shown in Figs. 4, 5 and 6, to receive lugs on the nozzle member 65 to be hereinafter described.

8 indicates a circular plate rotatably mounted within a recess formed by an inwardly extending annular shoulder 9 on the bung member 1 and provided with an opening 10 that is adapted to aline at times with the opening 4 in the web 3 and downwardly extending pins 11 that engage the segmental slots 5 in said web. The upper surface of the plate 8 is also provided with sockets 12 75 for the purpose to be hereinafter described.

13 indicates a plate mounted on the under side of the bung member 1 and secured to the pins 11, said plate having its edge formed with a reduced portion as shown at 80 13^a forming an annular shoulder 14 that is slightly smaller in diameter than the interior of the bung member 1.

15 indicates a packing gasket inserted between the web 3 and the plate 13 and provided with an opening 15^a in alinement with the opening 13^b in said plate 13, said gasket 15 being also secured to the pins 11 for simultaneous movement of the gasket with said plate 13 and the plate 8 heretofore described.

16 indicates an annular packing gasket mounted between the lower edge of the bung member 1 and the upper surface of the reduced portion 13^a.

The nozzle member 2 has a vertical opening 17 therein in which is slidably mounted the delivery tube 18, said delivery tube being appreciably smaller in diameter than the opening 17 and having a pipe connection 19 100 on its upper terminal with a rotary valve 20 controlling the flow of liquid through said pipe 18. The lower terminal of the opening 17 is enlarged as shown at 17^a to conform in size to the opening 4 in the web 3, said opening 4 as well as the other openings adapted to aline therewith as heretofore described, being enlarged to permit reception of a wear ring 21 screwed to the lower terminal of the delivery tube 18.

22 designates a packing nut mounted in a threaded socket 23 in the upper terminal of

the nozzle 2 and 24 a packing ring to form an air-tight and liquid-tight joint with the delivery pipe 18.

25 indicates a lateral air vent nozzle communicating with the vertical opening 17 and adapted to receive an air supply tube 26 as shown in Fig. 1. The air entering the opening 17 proceeds downwardly around the pipe 18 into the keg A to vent it. The lower terminal of the nozzle member 2 is formed circular to conform to the interior of the bung member 1 as shown at 27 and is provided with diametrically disposed projections 28 that register with the spaces between the terminals of the flanges 6 heretofore described to permit entrance of the nozzle into the bung member 1.

29 indicate pins extending downwardly from the lower surface of the nozzle member that are adapted to enter the sockets 12 in the circular plate 8 heretofore described when the nozzle member is inserted into the bung member and then by rotating the nozzle member through an arc of substantially 120°, the lower terminal 17^a of the opening 17 is brought into alignment with the opening 4 in the web 3 and at the same time, the lugs 28 will be engaged by the inclined shoulders 7 on the flanges 6 to clamp said lugs and the nozzle into engagement with the bung member 1.

30 indicates a packing gasket mounted on the under surface of the nozzle member 2 and provided with an opening 30^a that coincides with the enlarged lower terminal 17^a of the opening 17 and openings 30^b through which the pins 29 extend.

In operation, the nozzle member 2 and the pipe 18, with its inner terminal and wear ring 21 moved into the enlarged opening 17^a, is inserted into the bung 1. The pins 29 upon the lower terminal of said nozzle member 2 engage the openings 12 in the valve member 8, which is secured to the plate 13, as hereinbefore described, and upon the rotation of the said nozzle member 2, the openings in the valve members 8 and 13 and packing ring 15, and said web 3, register with each other, and the pipe 28 is inserted through said openings into the receptacle containing the liquid. Air being let into the interior of the receptacle through the nozzle 25 and openings 17 and 17^a, the liquid will flow through the pipe 18 to the valve 20, where it can be drawn off at 9. The inclined shoulder 7 of the bung 1 engages the portions 28 of the lower terminal of said nozzle member 2, upon the rotation of said member 2, and locks it in a position whereby the openings of said web, packing, and valve members are held in registration with each other.

Having thus described my invention what I claim is:—

65 1. In a tapping device for kegs and bar-

rels, a bung member adapted to engage the keg or barrel, an integral web in said bung member intermediate of the ends thereof and provided with a delivery opening and segmental slots, a valve member revolvably mounted on said web and comprising plates located on the two sides thereof, one of said plates being provided with pins engaging the slots in the web, the other of said plates being secured to said pins, said plates being formed with aligned openings that are adapted to be moved into and out of alignment with the opening in the web, the uppermost plate being provided with sockets, and a nozzle member having pins adapted to engage said sockets when said nozzle member is in engagement with the bung member to rotate said valve member, said nozzle member provided with a longitudinal opening, a delivery pipe extending through said opening in the nozzle member and adapted to be inserted through the openings in the web and valve members, and into the keg or barrel, an air vent nozzle formed on said nozzle member and communicating with said longitudinal opening in the nozzle, and the diameter of the opening in said nozzle being greater than the diameter of the said delivery pipe so as to allow the air to pass into said barrel or keg.

2. In a tapping device for kegs and barrels, a bung member adapted to engage the keg or barrel, an integral web in said bung member intermediate of the ends thereof and provided with a delivery opening and segmental slots, a valve member revolvably mounted on said web and comprising plates located on the two sides thereof, said plates being secured together for simultaneous revolution over the segmental slots in the web, and provided with aligned openings adapted to move into and out of alignment with the opening in the web, and a nozzle member adapted to cooperate with the bung member and provided with means to rotate the valve member aforesaid, the bung member being provided with interior flanges having their adjacent ends spaced apart and their lower edges inclined, and the nozzle member provided with lugs adapted to enter between the ends of said flanges and to seat under the lower edge thereof, and said nozzle member provided with a longitudinal opening terminating in an enlarged opening at the lower terminal of said nozzle member, a delivery pipe having a wear ring upon its inner terminal, and inserted through said longitudinal opening, and said wear ring adapted to fit within the enlarged opening at the lower terminal of said delivery pipe, and said delivery pipe adapted to extend through the openings in the valve members and into the keg or barrel.

3. A tapping device for kegs and barrels comprising a cylindrical bung member

adapted to be removably secured in the keg or barrel, a web within said bung member intermediate of its ends, said web being provided with an opening and segmental slots, 5 a plate rotatably mounted within said bung member and having an opening adapted to align at times with the opening in the web, pins mounted on said plate and slidably engaging said segmental slots, the upper surface of said plate being provided with sockets, a plate mounted on the lower ends of said pins and having an opening in alignment with the opening in the first mentioned plate, a packing gasket between the web and 10 the last mentioned plate and mounted on the pins aforesaid, said packing gasket being provided with an opening in alignment with the opening in the last mentioned plate, the upper terminal of said bung member 15 having its inner portion provided with flanges, said flanges having their ends spaced apart and their lower edges inclined, a nozzle member adapted to coöperate with said bung member and having diametrically op- 20

posed lugs or projections adapted to enter 25 between the ends of the flanges on the bung member aforesaid to engage the lower edges of said flanges, integral pins formed on the lower terminal of said nozzle member adapted to engage the sockets in the uppermost plate aforesaid, and a packing gasket mounted on the lower surface of said nozzle and adapted to seat upon said plate, said nozzle being formed with a delivery opening adapted to align with the openings in the 30 web and plates within the bung member aforesaid, and said nozzle member having a longitudinal opening formed therethrough, a delivery pipe mounted therein and adapted to extend through the openings in said valve 35 members, and the web and packing members, and into the keg or barrel.

In testimony whereof I affix my signature in presence of two witnesses.

FRIEDRICK GITTINGER.
